DESIGN FOR A HOLDER FOR BOTTLES

Horace G. Jackson, Woodstown, N. J.

Application February 26, 1944, Serial No. 112,726

Term of patent 14 years

(Cl. D58—4)

To all whom it may concern:

Be it known that I, Horace G. Jackson, a citizen of the United States, residing at Woodstown, in the county of Salem and State of New Jersey, have invented a new, original, and ornamental Design for a Holder for Bottles, of which the following is a specification, reference being had to the accompanying drawing, forming part thereof.

Figure 1 is a plan view of a holder for bottles showing my new design,
Figure 2 is a side elevational view, and
Figure 3 is an end elevational view thereof.

I claim:

The ornamental design for a holder for bottles, as shown.

HORACE G. JACKSON.
